(57) **CLAIM**

The ornamental design for a frame for crutches as shown and described.

DESCRIPTION

FIG. 1 is a perspective view of a frame for crutches, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view thereof;

FIG. 9 is a front view of the frame for crutches shown in use with environment and with symbolic break lines;

FIG. 10 is an enlarged view of the portion enclosed in dot-dash broken lines in FIG. 1;

FIG. 11 is an enlarged view of the portion enclosed in dot-dash broken lines in FIG. 6;

FIG. 12 is an enlarged view of the portion enclosed in dot-dash broken lines in FIG. 7; and,

FIG. 13 is an enlarged view of the portion enclosed in dot-dash broken lines in of FIG. 8.

The broken lines in the drawings shown in FIG. 9 are for purposes of illustrating environment only and form no part of the claimed design. The article in FIG. 9 is shown with symbolic breaks in its length by pairs of breakaway lines. The appearance of any portion of the article between the symbolic breaks in FIG. 9 forms no part of the claimed design. The dot-dot broken lines in FIGS. 1, 6, 7, 8, and 10-13 illustrate portions of the article that form no part of the claimed design. The additional dot-dash broken lines enclosing portions of the design in FIGS. 1, 6, 7, 8 and 10-13 are enlargement borders that form no part of the claimed design.
